UNITED STATES PATENT OFFICE.

JAMES J. O'BRIEN, OF PHILADELPHIA, PENNSYLVANIA.

GAME APPARATUS.

Application filed July 3, 1924. Serial No. 723,878.

To all whom it may concern:

Be it known that I, JAMES J. O'BRIEN, a citizen of the United States, residing at Philadelphia, in the county of Philadelphia and State of Pennsylvania, have invented 55 certain new and useful Improvements in Game Apparatus, of which the following is a specification.

My invention relates to game apparatus 10 and its object is to provide apparatus with which games analogous to the well known game of polo, may be played.

These objects, and other advantageous ends which will be described hereinafter, I 15 attain in the following manner, reference being had to the accompanying drawings in which

Figure 1 is a plan view of apparatus constructed in accordance with my invention,

Figure 2 a front view of the apparatus shown in Figure 1,

Figure 3 a section on line 3—3 of Figure 1,

Figure 4 an enlarged section on line 4—4 of Figure 2, and

Figure 5 a perspective view of an element which forms a part of my invention.

Referring to the drawings, 1 indicates a 30 casing, hereinafter called a game board, having a series of score lines 2 on its upper face 3, a goal 4 at each end of the series, and a slot 5 extending from one goal to the other. A member 6, hereinafter called the indicating member, is movable within a 35 slot from score mark to score mark to indicate the progress of the winning player toward the goal. It consists of a plate 7 having extended parts 8, 9 and 10, and is carried by a rod 11 secured thereto by nuts 40 12 and extending through slots 13 in opposite sides of the casing, the slots extending substantially the length thereof. The lower walls of these slots are provided with aligned notches 14 adapted to hold rod 11 45 in score indicating position. Each slot is reinforced by a metallic member 15. Rod 11 is provided on one end with a knob 16 whereby it may be swung to bring either extension into view above slot 5, and, on the other end, with a detachable stop 17 to

prevent it from being accidentally pulled out of the slot. A pair of members 18 are mounted in the ends of slots 13 and are adapted to swing into position at the goals 4 in certain parts of the game to indicate 55 that one of the players is entitled to kick for goal. Each of these members 18, hereafter called defense members, consists of a support 19 having an extended part 20, and is carried by a rod 21 secured to the support by a pair of nuts 22 and extending through the ends of slots 13. Rod 21 is provided on one end with a knob 23 whereby the rod may be turned to bring the extended part into view above the slot, and, on the other end with a stop 24 for preventing the rod from being accidentally pulled out of the slot.

Each player is represented by a color. Assuming blue and red to be the colors, 70 indicating member 6 will be blue on extension 8, red on extension 9 and blue on one half of extension 10 and red on the other half and one of defense members 18 is blue 75 and the other red.

A block 25, which may be considered as representing the ball, has two opposing surfaces blue and two opposing faces red, the other two faces being white or of some other neutral color.

To start a game indicating member 6 is placed midway between the goals and knob 16 manipulated to bring extension 10 in the uppermost position. One of the players then rolls the ball. If, when it stops, its top face is blue, the blue player has the ball. He then rolls again and if the top face is again blue, indicating member 6 is moved one notch toward the blue goal and blue scores a point. If the top face is red the red player gets the ball, and if, upon rolling, its top face is red indicating member 6 is moved one notch toward the red goal. If a neutral face comes up it indicates that the ball is out of bounds. The ball is again rolled to determine to which player it belongs, and the game proceeds as before. When either player has succeeded in scoring sufficiently to carry the indicating member to the score line adjacent his goal, the defense member 100

carrying his adversary's color is swung into its upper position to indicate defense of the goal. The player who has reached this position is then entitled to "kick for goal" 5 which is made by rolling the ball. If his color is up he wins the goal; if his opponent's color is up the player loses the goal and the ball goes to his opponent.

The points obtained may be the same as 10 those in polo or may be as agreed upon by the players. The player making the largest number of points in a specified time is the winner. Any suitable rules and penalties may be agreed upon to make the game interesting.

While I have described my invention as taking a particular form, it will be understood that the various parts may be changed without departing from the spirit thereof, 20 and hence I do not limit myself to the precise construction set forth, but consider that I am at liberty to make such changes and alterations as fairly come within the scope of the appended claims.

Having thus described my invention, what 25 I claim as new and desire to secure by Letters Patent is:—

1. A game board having a series of score marks on its face and a goal at each end 30 of the series; a member depending upon manipulation of a player for making a score, and an indicating member characterized by having means for distinguishing the players arranged in the board for movement from mark to mark toward a goal when a player makes a score.

2. A game board having a series of score marks on its face, a goal at each end of the series and a slot extending from goal to 40 goal; a member dependent upon the manipulation of a player for making a score, and an indicating member characterized by having means for distinguishing the players arranged in the board for movement within the slot from mark to mark toward the goal when a player makes a score.

3. A game board having a series of score marks on its face, and a goal at each end of the series; a block, having scoring indicia 50 on its faces, adapted to be rolled by a player to make a score, and a rotary indicating member having means for distinguishing the players arranged in the board for movement from mark to mark toward a goal when the player makes a score.

4. A game board having a series of score marks on its face, and a goal at each end of the series; a block, having faces of differing colors serving as scoring indicia, adapted to 60 be rolled by a player to make a score, and a rotary indicating member having color differentiated faces corresponding with the scoring indicia movable from mark to mark toward a goal when the player makes a score.

5. A game board having a series of score marks on its face, a goal at each end of the series and a slot extending from goal to goal; a member adapted to be rolled by a player for making a score, and a rotary indicating member having player distinguishing characteristics mounted in the slot for indicating the plays and adapted to be moved from mark to mark toward the goal when a player makes a score. 75

6. A game board having a series of score marks on its face, a goal at each end of the series and a slot extending from goal to goal; a member dependent upon manipulation by a player for making a score; a member adjacent each goal adapted to be moved through the slot for indicating a play, and a member movable in the slot for indicating the progress of a player toward the goal. 80

7. A game board including a casing having a series of score marks on its upper face, a goal at each end of the series, a slot in its upper face extending from goal to goal and slots in the opposite sides of the casing, each having a series of notches corresponding with the score marks; a member adapted to be manipulated by a player for making a score; a rotatable member mounted in the notches and adapted to be moved from notch to notch as a player makes a score, and a score indicating member carried thereby and extending through the slot in the upper face. 90

8. A game board including a casing having a series of score marks on its upper face, a goal at each end of the series, a slot in its upper face extending from goal to goal and slots in the opposite sides of the casing, each having a series of notches corresponding with the score marks; a member adapted to be manipulated by a player for making a score; a rotatable member mounted in the notches and adapted to be moved from notch to notch as a player makes a score, and a score indicating member carried thereby having faces of differing color and extending through the slot in the upper face. 100

9. A game board including a casing having a series of score marks on its upper face, a goal at each end of the series, a slot in its upper face extending from goal to goal and a slot in each side having notches corresponding with the score marks; a member adapted to be manipulated by a player for making a score; a member projecting above the score marks and adapted to be moved from score mark to score mark when a score is made, and members mounted in the ends of the notched slots adapted to be moved into the slot in the upper face to indicate a play. 115

10. A game board including a casing having a series of score marks on its upper face, a goal at each end of the series, a slot in its upper face extending from goal to goal and a slot in each side having notches 120

corresponding with the score marks; a member adapted to be manipulated by a player for making a score; a rod rotatably mounted in the notches; an indicating member carried thereby and extending into the slot in the upper part of the casing; rods rotatably mounted in the ends of the side slots, and

members carried thereby adapted to be moved into the slot in the upper face to indicate a play.

In testimony whereof I have signed my name.

JAMES J. O'BRIEN.
